UNITED STATES PATENT OFFICE.

ALBERT E. GREENE, OF CHICAGO, ILLINOIS.

ELECTRIC FURNACE.

1,078,619.

Specification of Letters Patent.

Patented Nov. 18, 1913.

Application filed January 23, 1911. Serial No. 604,014.

To all whom it may concern:

Be it known that I, ALBERT E. GREENE, citizen of the United States, residing at Chicago, in the county of Cook and State of Illinois, have invented a certain new and useful Improvement in Electric Furnaces, of which the following is a full, clear, concise, and exact description.

My invention relates to electric furnaces in which heat is generated by electric current induced in an electrical resistor.

My invention is applicable to heating furnaces for cold material or for fluids or for metals to be melted or to be heated when charged into the furnace either in the cold or molten state, or both.

The object of my invention is to provide an efficient means of utilizing electric currents for heating by combining the heating effects of both primary and secondary transformer currents.

My invention contemplates more particularly in the combination with a suitable heating chamber for carrying the charge of a solid metal resistor forming the secondary of a transformer and a primary winding in inductive relation to said secondary, both said primary and said secondary circuits constituting resistors from which the heat generated by passage of electrical current therethrough may be transmitted to the charge or material to be heated.

Other features of my invention relate to the details of construction whereby the secondary electric circuit constitutes also a magnetic circuit for the transformer; and to means for controlling the induction of current in the charge in the furnace chamber.

The several features of my invention may be more readily understood by reference to the accompanying drawings, in which—

Figure 1 is a central, vertical section of one embodiment of my invention particularly adapted to melting metals; Fig. 2 is a central, vertical section of a round furnace showing another embodiment of my invention designed for either heating or melting or both; Fig. 3 is a similar view of a modified structure particularly adapted for heating material; Fig. 4 is a longitudinal, central section of a rotary type of furnace embodying my invention; Fig. 5 is a view, partly in section, of a heating unit in which the secondary constitutes a magnetic circuit

with respect to the primary and in certain cases constitutes the furnace chamber for carrying the charge; Fig. 6 is a sectional elevation of a modification of my invention for preventing excessive induction in the charge itself; Fig. 7 is a plan section of the furnace shown in Fig. 6; Fig. 8 is a sectional elevation of a furnace embodying special features of my invention, and designed for controlling the amount of induction in the charge.

Referring to Fig. 1, 1 is the main chamber forming the junction of the smaller annular chambers 2, 2. The primary coils 3, 3 are embedded in the refractory lining 4, 70 and the secondaries 7, 7 are preferably located in the bottom of the chambers 1 and 2 and covered with a refractory lining 6.

In Fig. 2, the main chamber 8 is a round pot or crucible. The primary 9, and the secondary 10, both constituting electrical resistors, are embedded just underneath the refractory lining 11 and inside of the same. A magnetic core 12 serves to increase the electrical efficiency of the furnace. 80

In Fig. 3 is shown a furnace suitable for heating any kind of material. The secondary may be made in two parts 15 and 16. The upper part 15 may have a shape corresponding to the bottom and sides of the chamber 13 in the walls of which it is embedded. The lower part 16 forms a close fitting joint with the upper part 15. These two parts 15, 16 also constitute a magnetic circuit, the direction of the magnetic flux being indicated by arrows. The primary 14 is preferably embedded in loose refractory material 18 inside the part 16; and the secondary circuit constituted by 15 and 16 is embedded in refractory material 19. Where 90 desired a layer of refractory material 20 may be applied over the inner surface of the crucible formed by the part 15. Where it is desired to melt brass, for example, this refractory material may be of fire clay. 100

A rotary furnace is shown in Fig. 4. It consists of a main shell 21 and two ends 23 and 24. Inlet and outlet holes are shown at 25, 25 which may be closed by covers 26, 26 or left open for continuous passage of material through the furnace or used for any other suitable purpose, such as for passage of gas through the furnace. Secondary resistors 27 are located in the lining 22 and primary resistors 28 are located in close 105 110

proximity thereto. Inside the cylinder may be located another cylindrical heating part 32 hung on trunnions 29. The diameter of the cylinder 32 is considerably less than the internal diameter of the cylinder 21, thus leaving an annular space 30 for the charge. The inner part 32 contains a core 31 preferably laminated. This core is inclosed in a casing 33 made in two or more sections insulated from each other by insulating material 34. This casing 33 is preferably made of manganese steel to cut down magnetic losses. Primary coils 35 are embedded in the refractory 37 and secondary resistors 36 outside the primaries 35. The secondary circuit preferably consists as shown of a number of closed circuits in parallel.

Fig. 5 shows a heating unit which may be used in the hereinbefore described furnace or which may itself serve, for instance, as the retaining vessel for heating fluids. This heating unit consists of a primary winding 38, and a closed tubular secondary circuit 39, 39 preferably made in two halves, as shown, in order to facilitate repairs. The terminals of the primary 38 may be brought out through the opening 43. The path of the magnetic field produced by an alternating current in the primary is shown in general direction by the arrows. The two halves of the secondary 39, 39 may be made of a metal more or less magnetic and thus serve to increase the magnetic lines of force flowing through the coils of the primary 38. The primary 38 may be embedded in refractory material 41 or retained in any other suitable way. Space 42 is left between primary 38 and secondary 39 for receiving a fluid charge to be heated. This may be charged through the opening 44, and poured out through the opening 43 or through any other suitable openings, or the heater may be used for the continuous passage of fluid therethrough.

Figs. 6 and 7 show a furnace heated only by heat generated in the secondary of a transformer. The heating chamber 45 is partly surrounded by the resistor 46, 47. Said resistor forms the secondary of a transformer of which 48 is the core and 49 the primary. The resistor is made of reduced cross-section in the part 46 where the heat is desired, and large cross-section where heat is not desired.

Fig. 8 shows an induction furnace provided with a secondary resistor 56 embedded beneath the chamber 50 in refractory material. The primary coil 51 is adjusted with respect to the secondary 56 by any suitable means such as screws 53, 53. The short, central core 52 is also movable by the screw 55. This arrangement provides means for limiting and controlling the induction of current in the secondary 56 and in material 65 in the chamber 50. The charge in the chamber

50 also forms a complete secondary circuit around the core 52.

By the furnaces of the types I have described above I can melt or heat such metals as brass, copper, aluminum, zinc, lead, and the like from the cold irrespective of their form. To melt aluminum, for example, the cold aluminum metal is charged into the chamber of a furnace such as shown in Figs. 1 or 2. The current may then be put on the primary, and the furnace chamber heated by conduction from both the primary and secondary resistors until the aluminum melts. Further heating may be regulated by the voltage applied to the primary. It is, of course, preferable to keep the chamber full of reducing gas to prevent oxidation of aluminum. My invention aims primarily to provide suitable means for heating material in the form of small pieces or scrap, and subsequently when the pieces are fused together or melted, heating it by induced currents in the charge itself. By use of the furnace shown in Fig. 8 the induction may be controlled by varying the amount of magnetic flux encircling the charge constituting a secondary circuit.

When it is desired to heat material, for example to anneal steel castings, a furnace designed as shown in Figs. 2 or 3 may be used. When it is desired to heat liquids the secondary may be designed to hold these as shown in Fig. 3 or Fig. 5.

I am aware that it has been suggested to use a carbon crucible or a platinum or other metal crucible to heat a charge contained therein by currents induced from a primary through the aid of a magnetic core, and I do not claim such an arrangement.

I do not limit my invention to the use of solid secondary resistors as in certain cases these resistors may even melt and subsequently solidify again on the cooling of the furnace.

It is also understood that I do not limit myself to the use of metal for the secondary resistor but may use carbon or heated magnesite or any other suitable resistor.

What I claim is:—

1. In an electric furnace, the combination with a furnace chamber, of a transformer having a primary and a secondary coil both constituting resistors and arranged in proximity to said chamber, whereby heat generated in said primary and secondary coils is conducted to the charge in the furnace chamber.

2. In an electric furnace, the combination with a furnace chamber, of electric resistors constituting the primary circuit for an alternating electric current flow, electrical resistors arranged in inductive relation to said primary circuit and thereby constituting the secondary circuit, said electrical resistors being arranged in proximity to said furnace

chamber; whereby heat developed in said resistors is transformed to the charge in said furnace.

3. In an electric furnace, the combination 5 with a furnace chamber, of a primary winding having its turns embedded in the walls of said chamber and distributed in parallel relation to the interior surface of said chamber, a magnetic core encircled by said primary winding, and a secondary winding 10 likewise embedded in the walls of said chamber in parallel relation to the interior surface of said chamber.

4. In an electric furnace, the combination 15 with a furnace chamber, of a primary winding having its turns embedded in the bottom wall of said chamber, and a metallic core likewise embedded in the bottom wall of said furnace and having a central, vertical

portion concentric of the coils of said primary winding and a plate-shaped upper portion, said plate-shaped portion likewise constituting a secondary circuit.

5. In an electric furnace, the combination 20 with a furnace chamber, of a primary winding having its turns embedded in the bottom wall of said chamber, of a secondary consisting of an upper part 15 and a lower part 16, said parts 15 and 16 likewise constituting 25 a magnetic circuit.

In witness whereof, I, hereunto subscribe my name this twentieth day of January, 30 A. D., 1911.

ALBERT E. GREENE.
